UNITED STATES PATENT OFFICE.

ELGIN F. PAQUIN, OF CHARLESTOWN, NEW HAMPSHIRE, AND CHARLES C. PAQUIN, OF SPRINGFIELD, VERMONT.

HEATING-STOVE.

1,112,027.

Specification of Letters Patent.

Patented Sept. 29, 1914.

Application filed July 3, 1911. Serial No. 636,777.

To all whom it may concern:

Be it known that we, ELGIN F. PAQUIN, a citizen of the United States, residing at Charlestown, county of Sullivan, State of New Hampshire, and CHARLES C. PAQUIN, a citizen of the United States, residing at Springfield, in the county of Windsor and State of Vermont, have invented certain new and useful Improvements in Heating-
5 Stoves; and we do declare the following to be a full, clear, and exact description of the invention, such as will enable others skilled in the art to which it appertains to make and use the same.
10 This invention relates to stoves, and more especially to those of that type which are intended for heating purposes; and the object of the invention is to produce a stove having contiguous to its fire box an upright
15 dust passage controlled by a damper which is accessible through the stoking door, a check draft chamber forward of the dust passage and extending thence around and opening through the sides of the fire box
20 near its upper end, a draft passage forward of the dust passage and below said check draft chamber, extending thence downward and thence rearward around the lower portion of the fire pot and opening at the rear
25 into the top of the ash pit, a series of upright flues opening into the interior of the fire pot through ports in its wall, and a drum within the stove body above the fire pot for heating fresh air which is supplied
30 by an upright rear flue and passes into the reticulated dome at the top of the stove.
35

With these objects in view the invention consists in the improved construction, arrangement and combination of parts herein-
40 after fully described and afterward speci-
fically claimed.

In order that its construction and operation may be readily comprehended, we have illustrated a preferred embodiment of the
45 invention in the accompanying drawings, in
which:

Figure 1 is a side elevation of the stove; Fig. 2 is a central vertical sectional view thereof on the line 2—2 of Fig. 3, being
50 in a plane passing through the stove from front to rear; Fig. 3 is a similar view taken at right angles to Fig. 2, the plane passing through the stove from side to side; Fig. 4 is a horizontal sectional view on the
55 plane of the line 5—5 of Figs. 2 and 3.

Fig. 5 is a similar view on the plane of the line 6—6 of Figs. 2 and 3. Fig. 6 is a similar view on the plane of the line 7—7 of Fig. 3. Fig. 7 is a front elevation of the fire box with a portion of one corner broken away to show the manner in which the draft passages communicate. Fig. 8 is a horizontal sectional view on the plane of the line 9—9 of Fig. 2 omitting the ribs. Fig. 9 is a vertical sectional view on a plane 60 cutting through the fire box at an angle of 45° from the plane of Fig. 2. Fig. 10 is a sectional view on the horizontal plane indicated by the line 11—11 of Figs. 2 and 3. Fig. 11 is a horizontal sectional view on the plane of the line 12—12 of Figs. 2 and 3 omitting the ribs. Fig. 12 is a horizontal sectional view on the plane of the line 13—13 of Fig. 2. Fig. 13 is a detail sectional view of one of the dampers.

Referring specifically to the drawings, the numeral 21 designates the base of the stove in which is located the ash pit 22, and 23 the fire-box or fire-pot whose wall has an inturned flange 24 at its lower inner edge 80 upon which rests a circular rotary grate 25 which is formed with an inverted crown gear 26 meshing with a pinion 27 mounted on a shaft 28 and turnable by a crank 29 as usual in rotary grates, so that the grate may 85 be rotated within the fire pot when desired. The body of the grate is arched as best seen in Figs. 2 and 3, and carries upright bosses or pins 30, so that as the grate is oscillated or rotated continuously on its vertical axis 90 the fuel thereon is stirred by these bosses and the ashes sifted through the grate. In the front wall of the fire box 23 is an opening 31 above the grate 25 the purpose of which is to permit the removal of clinkers, 95 cinders or ashes from the fire box when a door 32 with which this opening is normally closed, is swung open. This opening may be used to dump the fire, by opening its door and rotating the grate until all the coals fall out through said opening into the ash pit 22.

During the operation of rotating the grate, it is desirable that the dust arising be carried off to the chimney and for this purpose we have provided in front of the fire box a slightly curved upright passage 33 which extends from the ash pit to the top of the fire box and is provided at its upper end with a damper 34 accessible through 105 110

the opening of door 35 through which the fire box is supplied with fuel. By opening a door 36 at the front of the ash pit and opening the damper 34 just referred to, a lively draft will be created through the dust passage 33 and carry all dust up through the chimney.

To supply air for combustion we have provided in front of the fire box and also in front of the dust passage a door 44 which gives access to a sector shaped passage 38 which extends about 90° around the front portion of the fire box and has its opposite ends overlapping the extremities of the circumferential draft passage 40 encircling the lower portion of the fire box (except in the front). This passage 40 has an opening 41 at the bottom of its rear portion which communicates with the ash pit, and openings 39 in the upper surface of the underlying portions of its extremities the purpose of which will be hereinafter described. The flooring of the passage 38 only extends about 45° around the fire box thus forming openings at each end of said passage which register with the underlying openings in the passage 40. Air admitted through the opening of door 44 into the draft passage 38 will pass through the openings in the extremities of this passage, enter the chamber 40, pass therethrough and through the opening 41 in its bottom, and enter the ash pit from whence it will pass to the grate.

The door opening 37 is closed by a damper 44 pivoted on a bolt 45 upon the inner end of which is a nut, while between the nut and the part through which the bolt passes is a coiled spring 46 (see Figs. 2 and 13). By screwing up the nut, the pressure of the spring is increased sufficiently to hold the damper in any position to which it may be turned, to open it, more or less, and the degree to which it is opened may be indicated by a pointer 47 operating in connection with a curved line of graduated figures (see Fig. 7) and when the operator has found that a certain adjustment of the damper produces the most favorable result, he can always readily adjust the damper to that point by observing the position of the pointer on the graduated scale. In each adjusted position the pointer rests in a notch in a curved bar 48 attached to the stove, and is held therein by the spring 46.

In order to provide for a check draft we form a curved air passage 49 in front of the dust chamber 33 and above the draft passage 38, and we furnish this chamber with a front opening and a damper 50 which is constructed and operated in all respects in the same manner as described in connection with the damper 44, being provided also with a pointer, curved bar and graduated scale as shown in Fig. 7.

The check draft passage 49 has the oppo-

site sides of its upper end provided with openings 51' which communicate with a circumferential passage 51 which surrounds the upper end of the firebox and communicates with downwardly and inwardly inclined ports 52, the air passing from the passage 51 through these ports into the firebox above the fuel and thence through the regular course to the chimney, thus checking the draft through the fuel in a well known manner.

The object attained by having the passage through which the air for combustion passes before entering through the grate, and the passage through which the check draft is passed before it enters the firebox above the fuel, pass substantially around the firebox is to bring the air into contact with the firebox and heat it thoroughly before it is permitted to pass through or enter into contact with the fuel in the firebox, the advantage of heating air for these purposes being too well known in the art to require particular description here.

We have provided, in contact with the wall of the firebox, a suitable number of semi-cylindrical vertical passages 53 which extend through the greater portion of the length of the firebox and each communicates, by means of a vertical row of ports 54 with the fuel in the firebox at different heights, the bottom ends of these passages being open to receive the air from the ash pit, and the top ends being closed to prevent the escape of the air except through the ports 54. The object of this arrangement is to admit the air heated in this passage through the flues 53 into the firebox through the ports 54 at various elevations so that heated air will thus be furnished to the fuel at many points. This will form carbon-monoxid gas which is combustible and will be consumed by fire, out of the carbon-dioxid gas, which is not combustible but which is formed by the contact of the heated air through the grate with the heated carbonic gases from the coal. This carbon-dioxid passes out through the fire and gives up about one half of the oxygen contained, thus forming, when contacting with the heated air entering through the ports 54, combustible carbon-monoxid, as before stated.

The firebox is surrounded by a series of radially extending vertical ribs 55, which extend from about two inches above the air draft passage 40 to about two inches below the top of the firebox. (See Fig. 4.) These ribs may be formed integral with the firebox or may be secured thereto in any suitable manner, and serve to prevent the firebox walls from warping under the conditions to which they are subjected. These ribs are surrounded by a sheet metal, cylindrical covering 56 which partly circumscribes the lower portion of the fire-pot and has the

5 rear and side portions of its lower edge terminating about 2 inches above the base 21, thereby forming an inlet by which the air may enter the passages 57. Circulating 57 are formed between these ribs 55, and air entering at the bottom thereof passes up between the firebox and the sheet metal covering 56, its course after leaving these passages being hereinafter described.

10 Another advantage due to the provision of these ribs is that the air circulating between the sheet metal covering 56 and the firebox, will prevent the sheet metal covering being heated to a sufficiently high degree to burn 15 off the blacking, and thus destroy the appearance of the stove.

The air passing through the passages 57 between the ribs 55 enters and passes through a series of tubes 58 located in the 20 body 42 and surrounded by the products of combustion rising from the fuel in the firebox, whereby they are thoroughly heated and continue to heat the air passing through them until it emerges from their upper ends 25 into the air chamber 73 formed by the perforated or reticulated dome 59 on the top of the stove, from which it passes in a highly heated state into the room in which the stove is located.

30 A passage 60 is provided on the exterior of the rear portion of the ash pit, having its lower end open as at 61, and controlled by a valve 62, and a pipe 63 leading from this opening communicates with the air in the room, or may be carried through the floor or walls so as to communicate with the outside air. At its upper end, the passage 60 communicates by an elbow 64, with a passage 65 which passes up in contact

40 with the rear surface of the wall of the firebox and between it and the sheet metal covering 56, the passage 65 communicating with a pipe 66 which passes up partially through the body 42 into a horizontal box

45 or drum 67 disposed within the body 42, said box or drum 67 having a vertical exit pipe 68 leading therefrom to a supplementary central dome 70 on the top of the stove, from which, the heated air may be

50 permitted to pass out as rapidly as may be desired by the turning of a damper 71. The drum 67 is provided with a curved baffle plate 72 forming about two-thirds of a cylinder and standing under the rear wall of 55 the pipe 68 with its free edges toward the front of the stove so that air passing into the said drum 67 through the pipe 66 will be deflected and caused to contact with the walls of the drum 67 in all of its parts.

60 By means of the construction and arrangement hereinbefore described, it will be obvious that we have provided means whereby an extremely large percentage of the heat evolved by the combustion of the coal is 65 utilized.

The foregoing is such a full and detailed description of the construction and operation of our improved heating stove that any further enumeration of its virtues at this point is deemed unnecessary, but we 70 desire it to be understood that we do not wish to confine ourselves to the exact construction and arrangements specifically described, for the obvious reason that many slight changes and variations may be made 75 without departing from the spirit or scope of the invention set forth in the appended claims.

What is claimed as new is:—

1. In a stove of the character described, 80 the combination of a base, a cylindrical fire pot having the lower end thereof disposed within the base and provided with a grate, a main body above said fire pot having communication therewith and with the chimney, a reticulated dome disposed on said main body and having therein an air chamber, an annular casing depending from the said main body, said casing having the front portion of its lower end secured to 90 said base, the remaining rear and sides thereof being spaced therefrom thereby forming a circumferential air inlet, air passages interposed between said fire pot and casing and communicating with said air inlet whereby the air may circulate through 95 said passages and protect the casing from the deteriorating effect of the heat radiating from said fire pot, and means whereby the air in said passages may be conveyed in 100 a heated condition to the air chamber in said dome.

2. In a stove of the character described, 105 the combination of a base, a cylindrical fire pot having the lower end thereof disposed within the base and provided with a grate, a main body above said fire pot having communication therewith and with the chimney, a reticulated dome disposed on said main body and having therein an air chamber, an 110 annular casing depending from the said main body, said casing having the front portion of its lower end secured to said base, the remaining rear and sides thereof being spaced therefrom thereby forming a circumferential 115 air inlet, radially extending wings formed on the side of said fire pot and adapted to coact with said casing to form vertically extending air passages, the lower ends of which communicate with said air inlet 120 whereby air may circulate through said passages and protect the casing from the deteriorating effect of the heat radiating from said fire pot, and means whereby the air in said passages may be conveyed in a heated 125 condition to the air chamber in said dome.

3. In a stove of the character described, 130 the combination of a base, a cylindrical fire pot having the lower end thereof disposed within the base and provided with a grate,

a main body above said fire pot having communication therewith and with the chimney, a reticulated dome disposed on said main body and having therein an air chamber, an annular casing depending from the said main body, said casing having the front portion of its lower end secured to said base, the remaining rear and sides thereof being spaced therefrom thereby forming a circumferential air inlet, air passages interposed between said fire pot and casing and communicating with said air inlet whereby the air circulating through said passages will protect the casing from the deteriorating effect of the heat radiating from said fire pot, and upright tubes arranged within said main body connecting said vertical air passages with the air chamber in said dome whereby the air in said passages may be conveyed to said chamber and heated in transit by the products of combustion in said main body.

4. In a stove of the character described, the combination of a base, a cylindrical fire pot having the lower end thereof disposed within the base and provided with a grate, a main body above said fire pot having communication therewith and with the chimney, a reticulated dome disposed on said main body and having therein an air chamber, an annular casing depending from said main body, said casing having the front portion of its lower end secured to said base, the remaining rear and sides thereof being spaced therefrom, thereby forming a circumferential air inlet, air passages interposed between said fire pot and casing and communicating with said air inlet whereby the air circulating through said passages will protect the casing from the deteriorating effect of the heat radiating from said fire pot, means whereby the air in said passages may be conveyed in a heated condition to the air chamber in said dome, an auxiliary air heating means arranged within said stove and comprising a drum located within said main body immediately above the fire pot and adapted to be heated by the products of combustion arising therefrom, means whereby outside air is conveyed to and heated by said drum,

and an upright pipe connecting said drum with said air chamber whereby the heated air in the former may be carried to the latter and conveyed to the exterior of the stove.

5. In a stove of the character described, the combination of a base, a cylindrical fire pot having the lower end thereof disposed within the base and provided with a grate, a main body above said fire pot having communication therewith and with the chimney, a dome disposed on said main body having therein an air chamber, an annular casing depending from the said main body, said casing having the front portion of its lower end secured to said base, the remaining rear and sides thereof being spaced therefrom, thereby forming a circumferential air inlet, air passages interposed between said fire pot and casing and communicating with said air inlet whereby the air circulating through said passages will protect the casing from the heat radiating from said fire pot, a drum located within said main body immediately above the fire pot and adapted to be heated by the products of combustion arising therefrom, means whereby outside air is conveyed to and heated by said drum, a baffle plate within said drum for deflecting the air passing therethrough whereby the latter may be brought into contact with the heated walls of said drum, and a vertically disposed pipe having its lower end communicating with said drum and its upper end entering said air chamber whereby the heated air in the former may be conducted to the latter and conveyed to the exterior of the stove.

In testimony whereof we have hereunto set our hands in presence of two subscribing witnesses.
